UNITED STATES PATENT OFFICE.

CORNELIUS C. HASTINGS, OF SPRINGFIELD, MASSACHUSETTS, ASSIGNOR TO MILTON BRADLEY COMPANY, OF SPRINGFIELD, MASSACHUSETTS, A CORPORATION OF MASSACHUSETTS.

PAPER-CUTTER.

1,123,190.

Specification of Letters Patent.

Patented Dec. 29, 1914.

Application filed February 3, 1912. Serial No. 675,303.

To all whom it may concern:

Be it known that I, CORNELIUS C. HASTINGS, a citizen of the United States of America, residing at Springfield, in the 5 county of Hampden and State of Massachusetts, have invented new and useful Improvements in Paper-Cutters, of which the following is a specification.

This invention relates to an improvement 10 in paper cutters.

Machines of this class are used for many different kinds of work.

The object of this invention is to improve 15 the type of machine referred to and render it more convenient when in use. This object is attained by the structure herein set forth which provides means whereby, after the 20 knife has been brought down, it will return immediately to an elevated position when released.

Other objects will appear in the following detailed description and annexed claims.

In the drawing forming part of this application,—Figure 1 is a plan view of a 25 paper cutter embodying my invention. Fig. 2 is a side view of the same.

The paper cutter comprises the usual table portion *c* at one end of which the knife *a* is pivoted in the usual manner. A spring *e*, 30 shown in Fig. 1, keeps the knife *a* against the edge of a cutter bar on the board.

Referring to Fig. 1, cards or paper of comparatively small area can be cut at the 35 end *x* of the cutter-board, while cards of comparatively large area can be cut only when the knife *a* is raised far enough to permit their insertion under the knife toward the part *y* of the cutter-board. Cards or 40 stock of other dimensions between the large and small sizes will be cut by raising the knife edge above the cutter-board proportionally between the points *x* and *y*.

In order to provide means whereby, after 45 the knife has been brought down it will return immediately to an elevated position when released, the following mechanism is provided: An arm *f* is fixed to the bolt *d* on which the knife is secured, and to the end 50 of this arm a flexible connection *g* is fastened. The other end of the connection *g* is fastened to a coiled spring *h*. A lever *b* is pivoted at *l* and when swung carries one end of the spring *h*, to which it is connected. A notched plate *k* on the side of the frame

serves to keep the outer end of the lever *b* 55 in any one of several adjusting positions. It is clear from the foregoing that the spring *h* will determine the position of the knife *a*. Accordingly, as the lever *b* is placed in one notch of the plate *k*, or another, the spring 60 *h* is put under more or less tension.

The operation is as follows:—If it is desired to cut stock to the limit of the machine's capacity, the lever *b* is fixed in the left-hand slot of the plate *k* thus putting 65 the spring *h* under its greatest tension and raising the knife-blade *a* so that the stock can enter under the knife adjacent the portion *y* of the cutter-board. The paper or other stock is then cut in the usual manner. 70 When the handle *t* is released, the tension of the spring *h* immediately raises the knife for another cutting operation. In a similar manner, if comparatively small stock is to be cut, then the lever *b* is placed in the right- 75 hand notch of the plate *k*. The tension put on the spring will in this case cause the knife to take up the position shown in Fig. 2.

For stock of a size between the smallest and largest sizes the lever *b* is placed in a 80 suitable one of the intermediate slots of the plate *k* to normally raise and keep the knife at a desired point.

By the use of the apparatus described, a 85 paper cutter of large capacity can be conveniently adapted for operating on all sizes of stock.

Applicant does not limit his invention to the specific form shown for it can be embodied in various forms.

What I claim, is:—

1. A cutter comprising a frame, a knife pivoted at one side thereof to coöperate with another side thereof for cutting operations, whereby as the knife is turned on its pivot 95 smaller or larger stock can enter under the knife to be cut, and means for elevating said knife to accommodate different sized stock comprising a resilient means to turn and elevate the knife in one direction, and lever setting devices including a rack secured to the frame to adjust said means to accurately determine the position the knife is to be elevated in accordance with the stock to be cut.

2. A cutter comprising a frame, a shaft 105 rotatably mounted therein, a knife fixed thereon, an arm also fixed thereon, a lever pivoted on the frame, a flexible spring con-

nection between one end of the lever and said arm whereby when said lever is turned to put the spring under tension, the arm will turn the shaft and elevate the knife, and means for setting the lever in one of several positions, each position arranged to determine the extent to which the tension of

the spring will raise the knife for the purpose described.

CORNELIUS C. HASTINGS.
